UNITED STATES PATENT OFFICE

MATSON C. TERRY, OF PHILADELPHIA, PENNSYLVANIA, ASSIGNOR TO WESTINGHOUSE ELECTRIC & MANUFACTURING COMPANY, A CORPORATION OF PENNSYLVANIA

REFRIGERATOR

Application filed November 19, 1925. Serial No. 70,117.

My invention relates to refrigerating machines and particularly to small capacity machines of the compression type which are suitable for household use and it has for an object to provide apparatus of the character designated which shall operate reliably and effectively for extended periods of time. It has for a further object to provide a refrigerating machine which shall embody a novel structure for condensing the refrigerant vapor and for dissipating the heat generated by the compression mechanism.

These and other objects, which will be made apparent throughout the further description of my invention, may be attained by the employment of the apparatus herein-after described and illustrated in the accompanying drawings in which Fig. 1 is a diagrammatic view of one form of refrigerating machine which is arranged in accordance with my invention; Fig. 2 is a view, in section, taken on the line 11—11 of Fig. 1 and Fig. 3 is an enlarged view, in sectional elevation, of the compression and condensing mechanism shown in Fig. 1.

It is generally recognized in the domestic refrigerator art that the installation of the compression mechanism, that is, the compressor and its driving motor, in a common fluid-tight chamber possesses numerous advantages inasmuch as a very compact arrangement is provided, the use of a stuffing box is avoided, quiet operation is insured and leakage of the refrigerant fluid is prevented. It is also recognized that generally air cooling is to be preferred to water cooling because it affords an easier method of installation. However, the problem of adequately cooling a totally enclosed compression mechanism in addition to condensing the required amount of refrigerant vapor has proven a very difficult one where it is desired to utilize air and not water as the cooling medium.

I have, however, conceived the idea of utilizing the exposed surfaces of the chamber enclosing the compression mechanism and of combining this chamber with a coil of the necessary length for condensing the refrigerant vapor. In addition, I have conceived the idea of so arranging the coil and the

chamber in relation to each other that a single source of air supply, such as a small motor driven fan or blower, may be utilized to produce the required cooling effect. Furthermore, I prefer to so arrange the blower with respect to the coil and the chamber that the cooling air is circulated circumferentially about both the coil and the chamber as I have found that in this way a maximum quantity of heat is absorbed in proportion to the amount of air circulated.

It has heretofore been proposed to absorb the heat of a totally enclosed compression mechanism by circulating or passing refrigerant vapor through the enclosing chamber. However, I have devised a machine which in part utilizes the condensed refrigerant fluid for absorbing the heat generated by the compression mechanism and inasmuch as liquids are generally better conductors of heat than gases I attain far more effective cooling.

As refrigerating machines of the household type generally operate intermittently in response to the temperature prevailing in the refrigerator box, I have improved their reliability of operation by providing a suitable reservoir for collecting the lubricant drainage during the inactive period of the machine. This reservoir is arranged so as to prevent any accumulation of lubricant in the vicinity of the enclosed motor. These and numerous other features, which will be described hereafter, cooperate to provide a refrigerating machine well adapted for domestic installation and for effective operation under the exacting requirements of household use.

Referring to the drawings for a more detailed description of my invention I show in Fig. 1 a cooling element or evaporator 10 which is adapted to be inserted within a refrigerator box. The evaporator 10 comprises an expansion chamber 11 and a freezing chamber 12 containing some noncongealable liquid such as alcohol and water. Disposed within the freezing chamber 12 is a container 13 for supporting a plurality of molds 14 for forming ice. Superimposed upon the expansion chamber 11 is a surge tank 15 which communicates with the expansion

chamber and which contains a level of liquid working fluid as indicated at 16. For removing the refrigerant vapor from the expansion chamber 11, an outlet conduit 17 is 5 provided which communicates at its inlet end 18 with the vapor containing portion of the surge tank 15 and which extends below the liquid level 16. Provided in the outlet conduit 17, at a point below the liquid level 16, is 10 an aperture or small opening 19 for entraining a small quantity of liquid working fluid in the vapor passing through the conduit 17. I may employ any one of many well known 15 refrigerating fluids in my machine. However, I prefer to employ a working fluid consisting of a refrigerant, such as ethyl chloride, and a lubricant, such as, mineral oil, which together form a homogeneous mixture or physical solution and which is disclosed 20 in the patent of A. A. Kucher No. 1,645,198, issued October 11, 1927 and entitled "Working Fluid for Refrigeration." The idea of 25 constantly entraining a quantity of such a liquid in the vapor removed from the evaporator is also disclosed in the patent of A. A. Kucher, No. 1,656,917 issued Jan. 24, 1928 and entitled "Refrigeration." An inlet 21 for admitting liquid working fluid to the expansion chamber 11 is provided in the evapo- 30 tor.

The inlet 21 of the evaporator connects, through a conduit 22, a float valve 23 and a conduit 24 with a condensing chamber 25. Surrounding the condensing chamber 25 is a 35 condensing coil 26 which is shrouded by an air casing 27 having its inlet arranged at 28 and its outlet at 29. A fan or blower 31 is provided in the inlet 28 for discharging air over the condensing coil 26 and the condensing chamber 25. The latter chamber is provided with a plurality of heat radiating fins 32 which are arranged radially upon the outer surface of the chamber inside of the air casing 27. As shown in Fig. 2, the inlet 28 40 of the air casing is arranged tangentially with respect to the condensing chamber so that the air discharged by the fan 31 passes along the condensing coil 26 and circumferentially about the condensing chamber 25.

50 As shown in Fig. 3, the condensing chamber 25 contains a compressor 33 which is preferably of the two-stage rotary type. The compressor 33 is driven through a shaft 34 by a motor 35. The motor 35 is arranged 55 within a fluid tight housing 36 provided with a removable plate 37 for permitting inspection of the motor. The condensate formed in the condensing coil 26 is conveyed by a conduit 38 to an inlet 39 provided in the lower 60 portion of the condensing chamber and this condensate together with the condensed refrigerant formed on the walls of the chamber 25 is discharged from the chamber through an outlet 41 which communicates with the 65 conduit 24. The inlet and outlet 39 and 41

are so located that a level of condensate, such as indicated at 42, is always maintained in the condensing chamber 25.

As shown in Fig. 1, working fluid is removed from the expansion chamber 11 of the evaporator by the compressor 33 through a conduit 43, a check valve 44, a lubricant reservoir 45 and a conduit 46 which communicates with a passage 47 provided in the motor housing 36. The check valve 44 is so arranged as 70 to prevent any flow of fluid from the reservoir 45 toward the evaporator 10. As shown in Fig. 3, refrigerant fluid is discharged from the compressor 33 through a conduit 48 provided with baffle or separator 49 arranged directly over the compressor 33. Any liquid entrained in the vapor discharged by the compressor is deflected downwardly by the baffle 49 and is collected in a lubricant receptacle 51 which surrounds the compressor 33 and is mounted upon the motor housing 36. Any vapor discharged by the compressor passes through an outlet 52 in the receptacle and enters the condensing chamber 25. Some of this vapor is condensed upon the walls of the chamber 25 while the remaining portion passes through an outlet 53 and is conveyed by a conduit 54 to the condensing coil 26. The lubricant receptacle 51 is provided with an overflow hole 55 so that a level of liquid, 90 such as indicated at 56, is always maintained 95 therein.

As the liquid contained in the receptacle is utilized for lubricating purposes, I have provided a conduit 57 and a passage 57' which communicate with the respective bearings of the compressor 33 for conveying lubricant thereto. The lubricant thus conveyed percolates downwardly through the compression mechanism to an intermediate shaft bearing 58 and is collected in a lubricant catcher 59 arranged above the motor 35. It is thence conveyed through a hollow portion 61 of the shaft 34 and collects in the lower portion of the motor housing 36 for lubricating a lower bearing 62. Lubricant is conveyed from the lower bearing 62 by means of a conduit 63 to the upper portion of the lubricant reservoir 45, shown in Fig. 1, which reservoir is connected to the inlet of the compressor 33. A check valve 64 is provided in the conduit 63 for preventing lubricant from returning from the reservoir to the motor housing. 110

115 The operation of the above embodiment of my invention is as follows:—

Assuming the refrigerating machine to be in operation, liquid working fluid is contained in the evaporator, the surge tank 15, the condensing coil 26, and the condensing chamber 25. The levels of the liquid in the surge tank 15, the condensing chamber 25 and the receptacle 51 are indicated at 16, 42 and 56 respectively. Air discharged by the fan 31 passes circumferentially around the condensing chamber 25 absorbing heat there- 120 125 130

from and also passes along the condensing coil 26. The air is confined about the condensing chamber and the coil by the air casting 27 and is discharged therefrom upwardly through the outlet 29.

5 The action of the compressor 33 maintains a pressure sufficiently low in the expansion chamber 11 to induce vaporization of the liquid working fluid contained therein. In 10 the vaporization process, heat is absorbed from the atmosphere surrounding the evaporator 10 and from the noncongealable liquid contained in the freezing chamber 12. As 15 most domestic refrigerating machines operate only intermittently in response to the temperature prevailing within the refrigerator box, the construction of the evaporator 10, as illustrated, possesses numerous advantages. As shown, heat is absorbed from the 20 surrounding atmosphere directly through the outer walls of the expansion chamber, thus insuring excellent heat conduction. On the other hand, the ice molds 14 are disposed within the freezing chamber 12 which contains 25 a substantial body of noncongealable liquid having a cold storage capacity sufficient to prevent melting of the ice during successive idle periods of the machine. In other words, the refrigerator box is cooled 30 by the direct expansion method while ice is formed by the indirect method, thus providing ideal conditions for maintaining the box temperature at a minimum and for manufacturing and maintaining a maximum quantity 35 of ice.

Because of the aperture 19, which is provided in the outlet conduit 17 within the evaporator, a small quantity of liquid working fluid is entrained in the vapor removed 40 from the expansion chamber 11 by the compressor 33. Upon the refrigerant vapor being discharged by the compressor at an increased pressure, this liquid impinges against the baffle 49 and falls downwardly 45 into the lubricant receptacle 51. The vapor passes outwardly through the outlet 52 and enters the condensing chamber 25. A portion of this vapor is condensed on the walls of the condensing chamber 25 while the remaining portion is conveyed by the conduit 54 to the condensing coil 26. This vapor is condensed in its downward passage through the coil 26 and is finally returned, in a liquid state, into the condensing chamber at 59. 55 This condensed refrigerant commingles with the condensate formed in the chamber 25 and is conveyed therefrom by the pressure prevailing within the condensing chamber to the conduit 24 and to the float valve 23. The outlet 41 is so arranged within the condensing chamber as to maintain a level of liquid refrigerant, such as indicated at 42, about the motor housing 36. All refrigerant which is condensed is thus compelled to circulate 60 about the motor housing prior to its passage

to the float valve. In this manner, a thorough cooling of the motor is effected at all times. Upon accumulation of some refrigerant in the float valve 23, the latter opens to permit the expansion chamber 11 to withdraw 70 this liquid refrigerant into the evaporator after which it is vaporized and again returned to the compression mechanism for a repetition of the cycle.

The liquid which is removed from the vapor by the baffle 49, shown in Fig. 3, and which collects in a lubricant receptacle 51, is composed, as stated heretofore, of a refrigerant and a lubricant which form a true physical solution. The receptacle 51 is 80 so arranged that this liquid immerses the compressor 33 and absorbs the heat which it generates. The absorption of the heat vaporizes off the refrigerant, which is the more volatile of the two components of the 85 solution, leaving a body of liquid which is substantially a lubricant. The refrigerant vapor incidentally formed is removed from the receptacle 51 through the outlet 52. This method of absorbing the heat of the compression mechanism as well as of producing a liquid suitable for lubricating purposes is disclosed in the patent of A. A. Kucher, No. 1,719,807, issued July 2, 1929, and entitled "Refrigerator." Any excess lubricating 90 fluid which is thus formed passes through the overflow connection 55 and commingles with the condensed refrigerant contained in the lower portion of the chamber 25 from whence it is conveyed to the evaporator. 100 Segregation or accumulation of this lubricant in the evaporator is prevented, however, by the constant entrainment of liquid in the outlet conduit 17, heretofore described.

Inasmuch as the interior of the motor chamber 36 is connected by a conduit 63 and the lubricant reservoir 45 with the suction conduit 46, there is a pressure difference prevailing between the condensing chamber 25 and the interior of the motor housing which corresponds substantially to the suction and discharge pressures of the compressor 33. This difference in pressure compels the lubricating liquid contained in the receptacle 51 to pass through the conduit 57 and passage 57' and enter the upper and lower bearings of the compressor 33. This lubricant then seeps or percolates downwardly through the working parts of the compressor to the intermediate bearing 58 and collects in the lubricant catcher 59, from whence it drains through the hollow interior 61 of the shaft 34 and lubricates the lower bearing 62. From the bearing 62 this lubricant passes through the conduit 63 to the lubricant reservoir 45 in which it becomes immediately entrained in the refrigerant vapor passing therethrough from the evaporator to the compressor. The refrigerant vapor entering the compressor has thus entrained therein a quantity of liquid 130

which is supplied both by the opening 19 within the surge tank and by the lubricating fluid removed from the motor housing. Sufficient liquid is in this way supplied to the inlet of the compression mechanism as will very effectively seal the same and insure efficient operation of the compressor.

Upon periodic stoppage of the machine, there is an immediate tendency for the pressures in the condensing chamber and in the evaporator to equalize. Such equalization of pressure is not desirable, however, inasmuch as it induces a rapid rise in the temperature of the evaporator and thereby reduces the capacity of the machine. Such an equalization of pressure is prevented by the check valve 44 which is so located that it prevents the fluid pressure leaking backwardly through the suction conduit 46 from entering the evaporator. This rapid back flow of pressure may, if the lubricant reservoir 45 and check valve 63 are omitted, spray all of the liquid contained in the conduit 46 as well as the connecting conduit 63 backwardly into the interior of the motor housing 36, thus dampening the entire motor 35 with lubricating liquid, a condition to be avoided, especially where motors of the commutator type are employed.

However, by providing the reservoir 45, a rapid back flow of pressure through the conduit 46 is absorbed within its relatively large interior and consequently there is no perceptible rush of pressure from the reservoir 45 into the conduit 63. As an added precaution against the spraying of any lubricant upon the motor I have provided the check valve 64 although I may dispense with the same. In addition, the receptacle 45 performs another function during the idle period of the machine inasmuch as during this period the lubricant contained in the receptacle 51 seeps downwardly through the compressor and into the lower portion of the motor housing from whence it is drained by the conduit 63 and accumulates in the reservoir 45 and not in the motor housing. In this manner, the accumulation of a substantial body of lubricant in the motor housing during the inactive period of the machine is entirely avoided. Upon the machine resuming operation, however, this lubricant is rapidly withdrawn from the reservoir 45 through the conduit 46 by the compressor 48 and again collected in the receptacle 51.

While I have shown my invention in one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. In a refrigerating apparatus, the combination of an evaporator, a compressor, a motor for driving the compressor, a fluid-tight casing enclosing the motor and the compressor and forming a condensing chamber, a second condenser encircling the chamber, and means for passing air circumferentially about both the condensing chamber and the condenser. 70

2. In a refrigerating apparatus, the combination of an evaporator, a compressor, a motor for driving the compressor, a fluid-tight casing enclosing the motor and the compressor and defining a condensing chamber, a condensing coil surrounding the condensing chamber, and means for discharging air circumferentially about the condensing chamber and over the condensing coil. 75

3. In a refrigerating apparatus, the combination of an evaporator, a compressor, a motor for driving the compressor, a fluid-tight casing enveloping the motor and the compressor and defining a condensing chamber, a condensing coil surrounding the condensing chamber, means for passing air circumferentially about the condensing chamber and over the condensing coil, and means for liberating the air from the upper portion of the condensing coil and the chamber. 85

4. In a refrigerating apparatus, the combination of a condenser, a compressor, a motor for driving the compressor, an evaporator disposed at a higher elevation than the motor, a receptacle for supplying lubricant during the operation of the machine and a reservoir disposed at a lower elevation than the motor for collecting the lubricant during the idle periods of the machine. 100

5. In a refrigerating apparatus, the combination of a condenser, an evaporator disposed at a higher elevation than the condenser, a compressor, a motor for driving the compressor, a common housing for both the motor and the compressor, a receptacle for supplying lubricant to the working parts of the compression mechanism, and a reservoir disposed at a lower elevation than the motor for collecting the lubricant. 105

6. In a refrigerating apparatus, the combination of a condenser, a compressor, a motor for driving the compressor, a housing for the motor, an evaporator disposed at a higher elevation than the motor, communicating means provided between the evaporator and the inlet of the compressor, an oil reservoir provided in said communicating means, and a drainage connection provided between the motor housing and the reservoir. 115

7. In a refrigerating apparatus, the combination of a condenser, a compressor, a motor for driving the compressor, a housing for the motor, an evaporator, communicating means provided between the evaporator and the inlet of the compressor, an oil reservoir 120

provided in said communicating means, a drainage connection provided between the motor housing and the lubricant reservoir, and means provided in the communicating means and located between the lubricant reservoir and the evaporator for preventing the return flow of fluid from the lubricant reservoir to the evaporator.

8. In a refrigerating apparatus, the combination of a condenser, a compressor, a motor for driving the compressor, a housing for the motor, an evaporator, communicating means provided between the evaporator and the inlet of the compressor, an oil reservoir provided in said communicating means between the housing and the evaporator, and means provided in said communicating means and disposed between the oil reservoir and the compressor for preventing the return flow of fluid from the compressor to the oil reservoir.

9. In a refrigerating apparatus, the combination of a condenser, a compression mechanism disposed within the condenser, an evaporator disposed at a higher elevation than the condenser, communicating means provided between the evaporator and the inlet of the compression mechanism, an oil reservoir disposed at a lower elevation than the compression mechanism and in said communicating means, a drainage connection provided between the compression mechanism and the oil reservoir, a check valve provided in the communicating means for preventing the back flow of fluid from the oil reservoir to the evaporator, and a second check valve provided in the drainage connection for preventing the back flow of fluid from the oil reservoir to the compression mechanism.

10. In a refrigerating apparatus, the combination of a condenser, an evaporator, a motor, a compressor driven by the motor, a housing for the motor subject to the suction pressure of the compressor, a lubricant receptacle subject to the discharge pressure of the compressor, means subject to the difference in pressure between the lubricant receptacle and the motor housing for conveying lubricant to the working parts of the compressor and the motor, a reservoir for returning lubricant from the motor housing to the inlet of the compressor, communicating means provided between the lubricant reservoir and the outlet of the evaporator, and a check valve provided in said communicating means for preventing the flow of lubricant from the reservoir to the evaporator during idle periods of the machine.

11. In a refrigerating apparatus, the combination of a compression mechanism, a fluid-tight casing enclosing the compression mechanism, a condenser disposed about the casing, an evaporator connected to the inlet of the compression mechanism, and means for con-

veying condensed refrigerant fluid from the condenser to the casing and thence to the evaporator, whereby the condensed refrigerant fluid passing through the casing absorbs a portion of the heat generated by the compression mechanism.

12. In a refrigerating apparatus, the combination of an evaporator, a compression mechanism, a fluid-tight casing forming a condensing chamber enclosing the compression mechanism, said compression mechanism being so disposed within the condensing chamber as to be partially surrounded by condensed refrigerant, a condensing coil disposed about the condensing chamber, and communicating means provided between the condensing coil and the condensing chamber.

13. In a refrigerating apparatus, the combination of an evaporator, a fluid-tight casing forming a condensing chamber, a condensing coil surrounding the condensing chamber and communicating therewith, and a compression mechanism so disposed within the condensing chamber as to be partially cooled by the condensed refrigerant formed in the condensing chamber and in the coil.

14. In a refrigerating apparatus, the combination of an evaporator, a motor, a compressor driven by the motor and superimposed thereon, a receptacle for retaining lubricant, said receptacle being so arranged with respect to the compressor that the lubricant contained therein is utilized to absorb the heat generated by the compressor, an overflow connection provided in the receptacle, a fluid tight casing enclosing the motor, the compressor and the receptacle, a condenser disposed about the casing, means for conveying condensed refrigerant from the condenser to the casing for absorbing the heat of the motor, means for conveying the condensed refrigerant together with the lubricant overflowing from the receptacle from the casing to the evaporator, and means for returning refrigerant fluid from the evaporator to the inlet of the compressor.

In testimony whereof, I have hereunto subscribed my name this sixteenth day of November, 1925.
